RECORD ALBUM

Richard I. N. Weingart, Glen Head, N. Y.

Application March 15, 1946, Serial No. 654,540

4 Claims. (Cl. 129—20)

1 This invention relates to phonographic record containers, and relates more particularly to an improved record album or book wherein the records are positively prevented from falling from the album, even though it is tipped upside down. The improved means for retaining the records in the album are effective to prevent accidental removal of the records whether the covers of the album are in open or in closed relation to each other.

Record albums generally consist of a plurality of top-opening record envelopes which are mounted between covers in the manner of pages in a book. The records thus rest upon the lower edges of the envelopes, and if the album is inadvertently turned upper edge downwardly, the records fall to the floor and are broken. Also, since the full weight of each record is borne by the envelope, there is a constant strain on the bindings, and in due time the album falls apart.

It is an object of the present invention to provide an album having a pin mounted on the rear cover, substantially centrally thereof, the pin extending through the central openings in the records contained in the album. At its forward end, the pin is formed with a ball terminal which may be of slightly larger diameter than the diameter of the main body of the pin. On its under surface this ball terminal is formed with a downwardly-projecting hook portion. The position of the pin relative to the envelopes is such as to cause the records to be suspended upon the pin rather than rest upon the lower edges of the envelopes.

It will be apparent from the foregoing that when the record album is in open position, the record in the uppermost envelope can be readily removed from the supporting pin since the ball terminal of the pin affords only a slight resistance to the movement of the record upwardly to disengage such record from the pin. On the other hand, if the record album, whether open or closed, is inverted, the records nevertheless cannot be readily disengaged from the pin because of the downwardly-projecting hook portion which, in such position, is uppermost. When a number of albums are laid horizontally in superimposed relation, the pin of each album will act as a spacer element whereby the weight of the upper records will not rest upon the lower records.

In the drawings:

Fig. 1 is a perspective view of a record album embodying the present invention.

Fig. 2 is a section taken on line 2—2 of Fig. 1.

Fig. 3 is a section taken on line 3—3 of Fig. 1.

2 Fig. 4 is an enlarged elevation of the album showing the relationship between the pin and the record when the upper edge of the album is positioned uppermost.

Fig. 5 is a broken vertical section of the album and the records, showing the manner in which the pin supports the records.

The record album of the present invention may comprise cover sections 10 and 11 which support, as leaves in a book, the usual envelopes 12 which are formed with a central opening 13. The upper edge of the envelope is open for the insertion of the record, as at 14, and midway between the terminals of the upper edge there is a concave cutout portion 15 to enable the records 16 to be readily removed from the envelope. All of the foregoing is conventional.

A supporting pin 18 is provided with a substantially circular shank portion 19 and a substantially flat base portion 20 which is suitably secured to the inner surface of back cover 10 in a position coinciding generally with the axis of openings 13 in envelopes 12. One means of accomplishing this is to employ a member 21 which may be a piece of relatively heavy paper or fabric which is adhesively secured to such inner surface of cover 10. At its outer end, pin 19 is formed with a generally hemispherical terminal 22 which may be of greater diameter than that of the shank 19 of the pin, or it may be of substantially the same diameter as that of the shank. On its lower surface, the terminal portion is formed with a projection or hook element 23.

Fig. 18 is formed with the usual central opening 24 which receives the spindle of the turntable (not shown). The greatest diameter of the enlarged outer terminal of the pin including the hook-like projection 23 is somewhat less than the diameter of record opening 24 to permit the record to be readily removed from the pin, all as shown in Fig. 4. The position of the pin relative to the envelopes is such as to cause the records 16 to rest upon the pin rather than upon the lower edge of the envelopes when the album is in closed vertical position. This spacing is shown at 26 in Fig. 5.

The use of the album will be largely clear from the foregoing description. Assume the album 50 to be empty. The records will be inserted in the envelopes and rest upon the lower edges of such envelopes, i. e., the position they would occupy when the album is in vertical position, upper edge uppermost. The last envelope (or lowermost when the album is lying flat on a table) is

then moved towards the lower cover, and because of the previous positioning of the record in the envelope the curved terminal of the pin readily enters the record opening. This action is repeated for the remaining records. The relationship of the pin to the envelope should be such that the records are suspended on the pin rather than rest upon the envelope when the album is vertical, as was earlier pointed out. This arrangement saves the album bindings and assures the records remaining flat.

When a record is to be removed from the album, the pin is readily removed from any or all of the records because of the illustrated contour of the curved terminal and the fact that the records are suspended from the pin with the projection or hook portion extending downwardly. If, however, the closed or open album is accidentally inverted, the records would normally fall out. The pin prevents this, especially in view of its formation, since the projection or hook portion is now uppermost and the records must pass this hook portion which affords a definite resistance to free movement.

While one form or embodiment of the invention has been shown and described herein for illustrative purposes, and the construction and arrangement incidental to a specific application thereof have been disclosed and discussed in detail, it is to be understood that the invention is limited neither to the mere details or relative arrangement of parts, nor to its specific embodiment shown herein, but that extensive deviations from the illustrated form or embodiment of the invention may be made without departing from the principles thereof.

What I claim is:

1. In a phonograph record album provided with covers and envelopes mounted therebetween in hinged relation for receiving the records, such envelopes being open at their upper edges and being closed along their bottom and opposed side edges and having openings in opposed walls thereof, the combination of means for preventing accidental displacement of the records from the album, such means comprising a pin rigidly mounted at its inner end on one of the covers and being located generally midway between the upper and lower and opposed side edges of the envelopes, such pin being arranged to pass through the central openings in the records positioned within the envelopes, the outer end of such pin being enlarged so as to provide a hook-like projection which impedes movements of the records mounted on the pin beyond the terminal thereof.

2. In a phonograph record album provided with covers and envelopes having generally circular, central openings therein, the envelopes being mounted between the covers in hinged relation for receiving the records, the combination of means for preventing accidental displacement of the records from the album, such means comprising a pin rigidly mounted at its inner end on one of the covers in a position generally at the axis of the envelope openings and ar-

ranged to pass through the central openings in the records positioned within the envelopes, the outer end of such pin being enlarged so as to form a hook-like projection, such projection impeding movement of the records mounted on the pin beyond the outer terminal thereof.

3. In a phonograph record album provided with covers and a plurality of envelopes mounted therebetween in hinged relation, the envelopes 10 being open at their tops and having generally circular openings substantially in the center thereof, the combination of means for preventing accidental displacement of the records from the album when such album is turned lower edge 15 upwards, such means comprising a pin rigidly secured at its inner end to the inner surface of one of the covers and being aligned generally with the axis of the envelope openings, the outer terminal of such pin being enlarged and being 20 formed on its lower surface adjacent such enlarged outer terminal with a hook-like projection, the pin being arranged to pass through the central openings in the records positioned within the envelopes, the hook-like projection 25 restraining movement of the records off the pin when the album is in said inverted position.

4. In a phonograph record album provided with front and back covers and open top envelopes, such envelopes having generally circular openings in opposed walls thereof and being mounted between the covers in hinged relation for receiving the records which are provided with small central openings therein, the combination of means for preventing accidental 30 displacement of the records from the album when such album is inverted, such means comprising a pin rigidly mounted at its inner end on the inner surface of the rear cover and being arranged to pass through said central openings in the records positioned within the envelopes, the pin being positioned substantially midway between the opposed side edges of the envelopes and also being so positioned relative to the lower 35 edges thereof as to support the records in spaced relation to said lower edges when the album is in vertical position, such pin being formed at its outer end with a substantially hemispherical terminal portion to facilitate entry of the pin into the record openings, such terminal portion being of greater diameter than the diameter of the pin and being formed on its lower surface with a hook-like projection which impedes movement of the records mounted on the pin beyond the terminal thereof when the album containing the records is inverted.
